OLIVER D. JOHANTGEN, OF CHICAGO, ILLINOIS, ASSIGNOR TO VICTOR ADDING MACHINE CO., OF CHICAGO, ILLINOIS, A CORPORATION OF ILLINOIS.

CLEAR-SIGNAL-PRINTING MECHANISM FOR LISTING-MACHINES AND THE LIKE.

1,396,215.

Specification of Letters Patent.

Patented Nov. 8, 1921.

Original application filed January 4, 1918, Serial No. 210,301. Divided and this application filed November 25, 1919. Serial No. 340,581.

To all whom it may concern:

Be it known that I, OLIVER D. JOHANTGEN, a citizen of the United States, and resident of Chicago, county of Cook, and State of Illinois, have invented certain new and useful Improvements in Clear-Signal-Printing Mechanism for Listing-Machines and the like, of which the following is a specification, and which are illustrated in the accompanying drawings, forming a part thereof.

The invention relates to listing machines, and has as an object the provision of means for printing a clear signal with the first item, without such clear signal being printed with a total or a sub-total although the accumulator will be clear in each of the three cases mentioned.

This application is a division of my application for patent on improvements in listing machines, filed January 4, 1918, Serial No. 210,301.

An illustrative embodiment of the invention is shown in the accompanying drawings, in which—

25 Figure 1 is an elevation of one side of a listing machine with many parts omitted as unnecessary to the present disclosure;

Fig. 2 is a detail longitudinal sectional view of the machine showing the printing elements in elevation;

Fig. 3 is a detail side view of the controlling link for the signal printing mechanism, the control shaft and a detail of the frame being shown in section;

35 Fig. 4 is an elevation showing a controlling element for the signal printing mechanism separated from other parts; and

Fig. 5 is a detail elevation showing the locks for the printing hammers and some 40 associated parts.

The machine is preferably assembled within and upon a sheet metal frame, two side elements of which are indicated at 40 and 48, having an inclined cover plate, as 44^a, 45 upon which the keyboard 45 is mounted, and transverse frame members one of which is indicated at 41. The keys, as 60, are arranged in rows numbered 1 to 9 in each row, there being as many rows as desired. 50 In the machine illustrated seven rows are indicated.

The keys may be depressed against the resistance of springs to coöperate with and determine the range of the movements of a

series of rack bars, one for each row of keys 55 and one of which rack bars is indicated at 52. These rack bars are adapted to turn a set of accumulator wheels located at the forward end of the frame, the depression of keys in each row thus determining the 60 amount of rotative movement imparted to the accumulator wheels.

There is also provided an operating handle, as 80, for actuating the rack bars and other movable parts of the machine, and 65 printing mechanism at the rearward end of the frame arranged to be set by the movements of the rack bars and operated by the handle. The operating handle 80 is secured to the shaft 82 at the opposite side of the 70 machine from that shown in Fig. 1, and a motion of oscillation in forward direction is given the shaft 85 by a link connection, not shown, and in the return direction by a master spring.

75 The recording or so-called printing mechanism may be assembled between and upon a pair of side plates of which the plate 48 is one, secured to the rear end of the corresponding frame plates 40. As shown, the 80 recording mechanism comprises a platen 28, ribbon guide 30, a series of number type bars 31 and a signal printing type bar 32. The number type bars 31, one for each row of keys, are pivotally supported at their lower 85 ends upon separate bell crank levers, as 59, shown as provided with an arcuate rack segment 198 and pivoted upon a shaft 56 extending between the side plates 48. To the other arm of the bell crank 59 is attached 90 a link 54, which is connected to the corresponding rack bar 52, so that the motion of the rack bar gives a corresponding upward movement to the associated type bar 31. The type bar 32 for the clear signal, having 95 but one type face thereon, is mounted on a fixed pivot 208, which may be applied to the adjacent side plate 48.

To rectify the type bars 31 in their alignment, a rectifying bar 195 is shown, which 100 forms the transverse member of a bail-shaped frame having side members, as 193, pivoted on a shaft 194 passing through the frame. This rectifying bar is moved toward the racks 198 just prior to each printing 105 operation, and engages between the teeth of the racks.

To cause the type to coact with the platen

with a hammer blow, the type bars 31 are pressed thereagainst by levers 187, overcoming the resistance of light springs 210 reacting between the lower ends of the type bars and the corresponding bell crank levers 59. Bar 32 may be normally held away from the platen by a spring 209 coiled about the pivot 208 and bearing on the frame. The action of levers 187 is caused by hammers 180, pivoted on a shaft 181, and each having a pin, as 189, projecting from its side for cam engagement with the corresponding lever. The hammers 180 are in turn actuated by springs 185, each secured to a projecting portion of one of the hammers and to a frame member 186.

The hammers 180 are normally held in position substantially parallel with type bars 31, 32, with levers 187 and the type bars 20 retracted and with springs 185 extended. For this purpose trip fingers 190, 191, are provided for engagement with notches in the lower ends of the hammers. The trip fingers 190, 191 are arranged in a row and 25 are pivotally mounted on a shaft 192 carried by the rectifying frame member 193. Normally the trip fingers 190, 191, are held against the front cross bar 195 of the rectifying frame 193, as by springs 196 anchored 30 to a cross bar 197, forming part of the rectifying frame. When the rectifying frame swings forwardly the trip fingers will move with it, each keeping its upper end in the notch of the corresponding hammer unless 35 prevented from doing so as will be explained. After movement, the hammers 180 are restored by means of a restoring rod 184, carried by crank arms 183.

The accumulator is preferably assembled 40 on a bracket 26, which may have the form of an inverted bail and may extend across the main frame of the machine at one end, being secured thereto by screws, as 46. A bell crank shaped member 116 may be pivoted at 45 each side of the member 26, as at 117, and these members 116 may carry a shaft 115 upon which a frame comprising end members 114 is carried. End members 114 are shown as having a slot, as 113, within which 50 the shaft 112, bearing the accumulator wheels 51, is guided for vertical movement. Movement of link 122 to the right will depress the accumulator wheels against the resistance of spring 118.

55 As is well understood in devices of the present type, the normal adding operation is accomplished by depression of the accumulator wheels into mesh with the advanced rack bars at the end of their forward stroke, 60 and keeping them in mesh during the return of the rack bars. When a total is taken the indicator wheels are engaged with the rack bars only during the outward movement of the rack bars. In the taking of a 65 sub-total, the indicator wheels are engaged

with the rack bars during both their outward and return movements.

When an oscillating control shaft, as 85, is employed, vertical movement of the indicator wheels 51 is most conveniently accomplished by the turning of an oscillating plate 120. As shown, this plate is pivotally secured against one of the side plates, as 40, of the main frame adjacent its forward end, as by a stud 121. Link 122 connects 75 the plate 120 with one of the arms of the adjacent bell-crank lever 116. While the spring 118 normally serves to hold the spindle 112 in elevated position, a second spring 123, acting between the link 122 and 80 the plate 120, serves to hold the spindle 112 in depressed position when the point of connection of the link 122 with the plate 120 has passed below the level of the stud 121.

To produce the desired movements of the 85 plate 120, a flanged disk 124, having three studs 125, 126, 127, is shown as mounted upon one end of the control shaft 85, and two links 128, 129, are provided for communicating motion from these studs to the 90 plate 120. The link 128 is effective for turning the plate 120 in both directions during the normal operation of the machine. On the other hand, the link 129 is effective for turning the plate 120 in both directions 95 during the taking of a total. In taking a sub-total, the link 129 is effective to turn the plate 120 in one direction, and the link 128 is effective to turn the plate 120 in the opposite direction. 100

The links 128 and 129 are pivotally connected with the plate 120 at opposite sides of its center, as at 131 and 132. As shown, the link 128 is formed with a hooked end 133. In the normal adding operation of the 105 machine, the hooked end 133 of the link 128 is engaged upon one side by the stud 126 as the control shaft 85 approaches the limit of its return movement. The link 129 is formed with oppositely facing shoulders 110 134 and 135. When this link is effective the shoulder 134 is engaged by the stud 127 at the beginning of the forward movement of the control shaft 85. Near the end of the forward movement of the control shaft 85 115 the stud 125 passes under the rear end of the link 129, for engagement with the shoulder 135 at the beginning of the return movement of the control shaft 85. When a sub-total is taken the stud 127 is engaged with the shoulder 134 at the beginning of the forward movement of the control shaft 85, but the link 129 is moved to an inoperative position 120 at the end of the forward movement of the control shaft. The indicator wheels 51 are 125 accordingly not lifted out of engagement with the rack bars 52 until the stud 125 becomes engaged with the hooked end 133 of the link 128.

The link 129 is normally supported in ele- 130

vated position out of the path of the studs 125 and 127. For this purpose it rests in the notched arm 136 of a vertically movable bracket 137, to which the stem 138 of the 5 total key 139 is connected. This method of supporting the link 129 permits of the lifting of the link for the engagement of the stud 125 with the shoulder 135 by the cam engagement of the stud with the rear end of 10 the link. As shown, the bracket 137 is formed with a vertical slot 141, and is slid- 15 ily held against the side plate 40 by a stud 142 which runs in this slot. A spring 140 serves for elevating the bracket 137 and total 20 key 139. To prevent movement of the total key 139, except when the machine is at rest or the control shaft 85 has reached the limit of its forward movement, the flange of the disk 124 extends into the path of an out- 25 standing arm 143 carried by the bracket 137, but the said flange has notches 144 and 145 which respectively register with the arm 143 when the machine is at rest and when the control shaft 85 has completed its forward movement.

The printing of a signal with the first item is desired, as usual, the invention contemplat- 30 ing that this shall be accomplished by permitting the actuation of the type bar 31 with the corresponding printing hammer 180 only when the accumulator 25 is clear. For this purpose each of the indicator wheels 51 of the accumulator is formed with a notch 214 (Fig. 2). A comb 215 (Fig. 4) extends 35 under the indicator wheels 51, and the notches 214 of all of the indicator wheels register with the teeth of the comb 215 only when the accumulator 25 is clear. When this condition exists the comb 215 may be 40 raised to enter its teeth in the notches 214. At other times the raising of the comb 215 is limited by the engagement of one or more of its teeth with the rims of the correspond- 45 ing indicator wheels. Furthermore, as the accumulator 25 is clear when a total or sub- 50 total is being printed, provision is desirably also made to prevent the raising of the comb 215 at this time, viz:—when the accumulator frame 114 has been lowered during the out- 55 ward movement of the rack bars 52.

As shown, the comb 215 is carried between a pair of crank arms, as 216 (Fig. 2), one at each end of the comb. These crank arms are fixed upon a rock shaft 217, and this 55 rock shaft extends between and is journaled at its opposite ends in the two ends of the accumulator frame 114. The rock shaft 217 accordingly rises and falls with the accumulator frame 114. Movement of the comb 215 is confined to a vertical plane by providing it at each end with a slotted arm 218, which engages the spindle 112 upon which the indicator wheels 51 are mounted. The rock shaft 217 is also provided with a crank 60 arm 219 intermediate its ends. This last 65

mentioned crank arm carries a crank pin 220. The function of these parts is to provide for the withdrawal of the hammer lock 190 when the raising of the comb 215 is permitted. To this end a link 222, having 70 a notched forward end for receiving the pin 220, extends rearwardly from this pin over the transverse frame member 41, and over the control shaft 85. At its rear end the link 222 is turned upwardly and has a pin 75 and slot connection 223 with the hammer lock 190. This pin and slot connection permits rearward movement of the rectifying frame 193 without dislodging the hammer lock 190 from the corresponding hammer 80 180.

It will be understood that raising of the comb 215 and withdrawal of the hammer lock 190, as in Fig. 2, are accomplished by the forward movement of the link 222. To 85 prevent raising of the comb 215 when a total or sub-total is to be printed, the link 222 is equipped with a pivoted latch member 224. When the accumulator frame 114 has been lowered in advance of outward 90 movement of the rack bars 52, as in taking a total or sub-total, the link 222 is lowered at its forward end and the latch becomes engaged with the transverse frame member 41, as in Fig. 3. This prevents forward 95 movement of the link 222, notwithstanding the fact that when the printing operation is to be accomplished the notches 214 of all of the indicator wheels 51 will have been brought into register with the teeth of the 100 comb 215. On the other hand, when a "first item" is to be printed the link 222 is moved forwardly in advance of the depression of the accumulator frame 114. Under these 105 circumstances the forward end of the latch 105 224 rides upon the top of the transverse frame member 41, as in Fig. 2.

When forward movement of the link 222 is permitted this is accomplished as the actuating handle 80 approaches the end of its 110 forward stroke. For this purpose the crank arm 199 on the control shaft 85 is formed with a contact shoulder 221. In order that the operation of the machine may not be interfered with when the link 222 is held 115 against forward movement, a yielding stud 225 is carried by the link for cooperation with the contact shoulder 221. As shown, the stud 225 is mounted at the lower end of a crank arm 226, which has pivotal connection with the link 222, and a stout spring 227 acts between the stud 225 and the link 120 for causing the link to move with the stud except when such movement is prevented.

I claim as my invention:

1. In a listing machine or the like, in combination, a signal printing type bar, a spring actuated printing hammer therefor, a lock normally holding the hammer against movement, a set of independently rotatable indi- 125 130

4. In a listing machine, or the like, in combination, item and total printing elements, 65 a set of indicator wheels, a set of rack bars coöperating with the indicator wheels and controlling the item and total printing elements, and a signal printing device operable only during item printing and when the indicator wheels are in a predetermined position and being prevented from operation at other times by the indicator wheels.
5. In a listing machine or the like, in combination, item and total printing elements, 70 a signal printing device, a set of indicator wheels preventing operation of the signal printing device, except when the indicator wheels are in a predetermined position, and a set of rack bars coöperating with the indicator wheels and controlling the item and total printing elements.
6. In a listing machine or the like, in combination, item and total printing elements, 75 an accumulator, devices coöperating with the accumulator and controlling the item and total printing elements, and a signal printing device operable only during item printing and when the accumulator is clear and being prevented from operation at other times by the accumulator elements.
7. In a listing machine or the like, in combination, a vertically movable accumulator frame, a set of indicator wheels mounted in 85 the said frame, each indicator wheel having a single peripheral notch, a set of inwardly and outwardly movable rack bars coöperating with the indicator wheels when the accumulator frame is depressed, item 90 and total printing devices including a set of figure printing type connected with each of the rack bars, signal printing mechanism including a printing hammer and a lock normally holding the said hammer against 95 movement, a movable detector bar carried by the accumulator frame and having a finger for entering the notch of each of the indicator wheels, a link connecting the hammer lock and detector bar, a frame member 100 extending under the link, a yielding pawl depending from the link adjacent the said frame member, means acting to depress the accumulator frame during inward movement of the rack bars for item printing and 105 during outward movement of the rack bars for total printing, and actuating means yieldingly operable upon the said link upon completion of the outward movement of the rack bars and while the accumulator frame 110 occupies the same position which it had during such movement.
8. In a listing machine, or the like, in combination, item and clear signal printing mechanisms, 115 a rectifying frame, a hammer lock for said clear signal printing mechanism carried by said frame, means operative upon printing a first item and inoperative during all other printing operations to withdraw said hammer lock.
9. In a listing machine or the like, in combination, a signal printing type bar, a vertically reciprocable number printing type bar, a horizontally reciprocable rack bar, a bell crank lever upon which the number 125 printing type bar is pivotally mounted, connection between the bell crank lever and the rack bar, an accumulator wheel movable
2. In a listing machine or the like, in combination, item and total printing elements, 5 the indicator wheels when the said openings are alined in a predetermined position but held against movement by contact with the corresponding indicator wheel when any one of the said openings is not so positioned.
3. In a listing machine or the like, in combination, item and total printing elements, 10 a signal printing device, a set of indicator wheels preventing operation of the signal printing device except when the indicator wheels are in a predetermined position, and a set of rack bars coöperating with the indicator wheels and controlling the item and total printing elements.
4. In a listing machine, or the like, in combination, item and total printing elements, 15 a signal printing type bar, a printing hammer therefor, a lock holding the hammer against movement, a set of independently rotatable indicator wheels each having a single opening, a set of inwardly and outwardly movable rack bars controlling the item and total printing elements and normally coöperating with the indicator wheels only during inward movement but coöperating with the indicator wheels during outward movement for total printing, mechanism for 20 withdrawing the said hammer lock comprising an element movable into the openings of all of the indicator wheels when the said openings are alined in a predetermined position but held against movement by contact with the corresponding indicator wheel when any one of the said openings is not so positioned, and additional means preventing movement of the said element last mentioned when the openings of the indicator wheels are alined in the said predetermined position by coöperation of the rack bars with the indicator wheels during outward movement.
5. In a listing machine or the like, in com-

into and out of engagement with the rack bar, hammers operable against the two type bars, triggers normally preventing movement of the said hammers, and means operable to release the trigger of the hammer associated with the signal printing type bar when the accumulator wheel is in a predetermined po-

sition at the beginning of the movement of the rack bar, the said means being inoperable to release the trigger when the accumulator wheel is brought to the said predetermined position by movement of the rack bar. 10

OLIVER D. JOHANTGEN.
